UNITED STATES PATENT OFFICE.

SAMUEL HAUGHTON WARREN, OF KEOSAUQUA, IOWA.

FEED-RACK.

SPECIFICATION forming part of Letters Patent No. 449,303, dated March 31, 1891.

Application filed April 4, 1889. Serial No. 306,036. (No model.)

To all whom it may concern:

Be it known that I, SAMUEL HAUGHTON WARREN, a citizen of the United States, residing at Keosauqua, in the county of Van Buren and State of Iowa, have invented a new and useful Feed-Rack with Shed Attachment, of which the following is a specification.

My invention relates to an improvement in feed-racks and sheds, in which a self-regulating feed-receiver operates in conjunction with a protected feed-saving manger and an adjustable or regulating slide in the rack and a protection against storms for stock in the sheds; and the objects of my improvements are, first, to provide a self-regulating feed-receiver in the upper part of the rack that will receive the feed at the top and convey the same to a manger beneath, the receiver being automatic in its nature, and to which the stock have access through openings in the sides and ends of the rack; second, to afford facilities for the self-regulation of feed, the reservation of feed, the saving of feed, the saving of labor, the protection of stock from accidents, and, third, a shed attached to the rack to protect the stock from storms.

I attain these objects by the construction illustrated in the accompanying drawing, in which is shown a perspective view of my device, and in which—

1 are vertical parts of the entire rack. 2 are the upper girts. 3 are the guards. 4 are the slides. 5 are the cleats. 6 is the top of the manger. 7 are boards inclosing the manger. 8 are slats inclosing the feed-receiver. 9 are braces. 10 are supports. 11 are truss-blocks. 12 are retaining-stakes.

Similar figures refer to similar parts throughout.

40 The lower girts 2 and guards 3 and supports 10 are fastened to vertical posts 1 by bolts passing through all of them, and the upper girts 2 are mortised into the vertical posts 1 at the top and nailed, constituting the frame-work of the rack. Braces 9 are nailed to the vertical posts 1 on the inside, and slats 8, nailed to the upper and lower girts 2 on the inside of same, constitute the feed-receiver.

45 The retaining-stakes 12 are secured at their tops at the upper portion of the manger and extended obliquely downward toward the center of the rack below the receiver. These

stakes serve to keep the material back from the manger and permit the animal to draw the hay out, and the accumulation of the hay deposited in the bottom of the manger is protected and held within, preventing the cattle from trampling the same down.

50 The slides 4 are kept in place by cleats 5, nailed to the top of the manger, and guards 3, and when closed is secured by a loose bolt passing into the post through the cleats 5 and slides 4.

The truss-blocks 11 are nailed in between the guards 3 and lower girts 2 and are to strengthen the guards.

55 The sub-posts 10 are to give extra width to the manger.

The girts 2 and slats 8 are nailed on the inside of racks.

60 By making the rack smaller at the top than at the bottom the feed is permitted to spread and become somewhat loosened at the side, so as to be more easily drawn out.

65 The shed is attained by extending vertical posts 1 on the back side and both ends of the rack higher than in front by nailing plates flat on top of vertical posts 1 at both ends and back side, letting plates extend beyond the vertical posts 1, and supported by braces from the end of the plate to the post beneath, to which the upper ends of the rafters of the shed are

70 nailed, and closing the opening by extending the slats 8 to the plates at the top or backs and ends of the rack and nailing them to the plate and closing the openings between the slats by battens. The end walls of the shed extend beyond the front of the rack sufficiently to shelter stock feeding at the rack, constituting the shed attachment, and it is labor-saving, because feed can be stored in large quantities and may be always reserved for bad weather. It protects from accidents by the manger being inclosed, preventing stock from accidentally falling into the manger, and the stock are protected from getting chaff into their eyes, because the mouth cannot be elevated higher than the eyes while feeding.

75 The shed attachment affords protection for stock and shelter from storms; also affords a driveway around the rack for cleaning and bedding in the rear of the rack and an approach in front of the rack for replenishing the same with feed. The formation for the

rack and shed is attained by setting all vertical parts of rack and shed in the ground or by using short posts or stone.

What I claim as my invention, and desire 5 to secure by Letters Patent, is—

In a feed-rack, the combination of a horizontal slatted manger having openings there-in through which the feed is taken, slides for opening and closing the openings, a feed-

holder above the manger, formed of a size less 10 than the manger and with vertical slats, a shed inclined from the top of the holder, and inclined retaining-stakes 12 in the manger, substantially as described.

SAMUEL HAUGHTON WARREN.
